PROTECTION FOR ELECTRON TUBES

Robert F. Holtz, Merchantville, N. J., assignor to
Radio Corporation of America, a corporation of
Delaware

Application October 31, 1944, Serial No. 561,280

4 Claims. (Cl. 315—119)

1

This invention relates to the protection of electron tubes, and more particularly to the protection of such tubes from damage which may be caused by abnormal current flow in two of its external circuits.

While over-current and under-current relays for this purpose are well-known, it is often necessary to afford protection at the same time against the possibility of abnormal current flow in two associated circuits of a tube; and it is sometimes undesirable, on grounds of cost, and more particularly of space, to use two relays. Thus, in the generation of high frequency heating currents, anode current rises steadily during the heating cycle; towards the end of the cycle, and sometimes in the middle of it, a substantial increase of anode current may occur which, if continued, will cause damage to the tube, and may at least cause it to lose emission. There is also the possibility of abnormal current flow in the grid circuit, and this may be either in excess of or below the normal operating grid current. An abnormal flow of grid current will not always be reflected in a change of anode current, particularly when the electrical characteristics of the load are changing; and it may be overlooked by an unskilled operator.

It is, therefore, an object of the invention to provide an improved method of and means for protecting an electron tube from damage which may be caused by abnormal current flow.

Another object is to provide an improved, compact and unitary relay for the prevention of abnormal current flow in two associated circuits of an electron tube.

A further object of the invention is to provide improved means for protecting automatically an electron tube from damage due to abnormal current flow which may not be evident to the operator.

These objects are achieved in one embodiment of the invention by inserting a resistor in each of two associated circuits of a tube, in such a manner as to procure equal and opposing voltages in each of the resistors. These voltages depend on the normal flow of current in the circuits in which they appear. A relay adapted to de-energize the tube or otherwise control its operation is connected with its actuating winding in shunt with the resistors. Any change, therefore, in the ratio of current in the two circuits will result in a voltage being impressed on the winding of the relay, and actuation of the relay.

Figure 1 of the accompanying drawing is a schematic representation of a triode with its as-

2

sociated circuits and embodying the relay of the present invention, and

Figure 2 is a schematic drawing similar to Figure 1, but showing the application of the invention to a tube with more than three electrodes.

An electron tube 10 is represented as having a cathode 12, a grid 14 and an anode 16. The anode circuit 18 of the tube includes a source of power, indicated generally at 20, for the anode, and the total impedance of this circuit (including impedance of the circuit within the tube itself) is represented by the block marked Z_p . Similarly, the block Z_g represents the total impedance of the grid circuit 22 of the tube.

A resistor AC is connected partly in the anode circuit and partly in the grid circuit; the resistor is also connected at an intermediate tapping point B to the cathode 12 by a conductor 24. Point B is so chosen on AC that the voltage drop from A to B is equal to that from B to C. An example will illustrate what value to select for the resistor AC and how to determine the point B.

An oscillator in commercial use in high frequency industrial heating consists of two RCA Type 892-R tubes connected in parallel. These tubes are very expensive, and it is highly desirable that they should not be operated at other than their proper ratings, particularly for any length of time. In normal operation, D. C. anode current should be of the order of 3.5 amps., and grid current approximately 350 m. a. If a loss of 100 volts can be tolerated in the anode circuit due to the relay, then BC may have a resistance of approximately 30 ohms. Since the voltage drop across AB must equal that across BC, the resistance of AB will be approximately 300 ohms, and the total resistance of AC about 330 ohms.

By-pass condensers 32 and 34 are connected in shunt with the resistors AB and BC respectively, so that the voltage appearing across these two resistors shall not be affected by current of radio frequency flowing in either of the circuits 18 or 22.

An actuating winding 26 of a relay 28 is connected in parallel with the resistor AC, current in the secondary circuit 36 of the relay being employed to cut off the supply of power from the source 20. In practice, the secondary relay circuit 38 is connected with the various auxiliary controls or interlocked safety devices which automatically cut off the supply of power to the anode 16 when, for example, any of the doors giving access to the apparatus are opened.

If current in the anode circuit 18 rises to 4 amps., the voltage drop across BC rises to 120

volts. If, therefore, it is desired that anode current shall not exceed 4 amps., the relay 28 is so designed as to be actuated when a voltage of 20 volts appears across the winding 26. In that event, and if anode current remained unchanged, the relay would also be actuated if grid current exceeded 400 m. or fell below 260 m.

Thus, operation of the relay depends on a variation in the ratio of current normally flowing in the two associated circuits of the tube, this in turn causing a variation in the ratio of the voltage drops across AB and BC. The circuit illustrated constitutes a balanced bridge circuit with the resistors AB and BC forming two adjacent arms of the bridge, the impedances Z_p and Z_g constituting the other two adjacent arms and the winding 26 constituting a conjugate arm of the bridge.

Many variations of the embodiment described are within the scope of the invention. It is not limited to the use of an electron tube as an oscillator, but may be employed in an amplifier, or wherever the ratio of current normally flowing in two circuits of a tube is subject to variation. The invention is equally applicable to tubes which have more than three electrodes, in which event the resistors AB and BC may be contained in the two circuits of the tube whose current is most likely to vary. Fig. 2 illustrates the application of the invention to a tetrode, parts which are common to Figs. 1 and 2 being designated by the same reference numerals. In Fig. 2 the tube 10 is shown as having a screen grid electrode 36 in addition to the three electrodes mentioned in connection with Fig. 1. A circuit 38 connects this electrode to the cathode 12 and includes a source of power 40 for the screen grid. If the circuits 22 and 38 are to be protected from an abnormal flow of current, the resistor ABC is connected in these two circuits in the manner indicated above.

Other departures from the embodiments illustrated in Figs. 1 and 2 may include the use of a gas-filled tube or other form of relay in place of the mechanical relay 28, and the utilization of current in the secondary relay circuit 30 to give an alarm or perform some other protective or control operation in place of, or in addition to de-energization of the tube 10.

It should be noted that the relay will not be actuated if both grid current and anode increase or decrease simultaneously by such amounts that the balance of potential across AB and BC is not sufficiently disturbed to impress the required actuating potential on the winding 26. On the other hand, the arrangement here described is more effective than a prior art relay if one of the two currents increases while the other decreases.

There has thus been described a simple method of and means for protecting an electron tube from damage due to an abnormal flow of current in its associated circuits. Two voltages representative of current in two of the tube circuits are balanced, and any unbalance of these voltages is

used to create a third voltage which is employed, in turn, to de-energize the tube.

I claim as my invention:

1. A system for protecting an electron tube, which has external grid and anode circuits, from damage due to an abnormal flow of current in either of said circuits, said system comprising a resistor connected in each of said circuits to form a balanced bridge circuit on normal flow of current in said circuits, said resistors forming two of the arms of said bridge, and the remaining total impedances of each of said circuits forming the other two arms of said bridge, means for adjusting the relative values of said resistors, and a relay for de-energizing said tube having its actuating winding connected across opposite points of said bridge, whereby on abnormal flow of current in either of said external circuits the balance of said bridge will be disturbed and said relay actuated to de-energize said tube.

2. Apparatus for protecting an electron tube from damage due to an abnormal flow of current in external grid and anode circuits, which comprises means for deriving a potential proportional to current flowing in one of said circuits, means for deriving a second potential equal in amount and opposite in direction to said first potential and proportional to current flowing in another of said circuits, means for adjusting the balance point of said potentials, and means responsive to a variation in the ratio of said potentials for de-energizing said tube.

3. An electron tube having at least a cathode, an anode and a grid, an external circuit connecting said cathode to said anode, a resistor in said circuit of such value as to establish thereacross, by reason of normal current flow in said circuit, a voltage drop of predetermined amount, a second external circuit connecting said grid to said cathode, a resistor in said second circuit of such value as to establish thereacross, by reason of normal current flow in said circuit, a voltage drop equal to that of said first-mentioned resistor, means for adjusting the relative values of said resistors, a capacitor connected in parallel with each of said resistors, and means responsive to an inequality of said voltage drops for de-energizing said tube.

4. A unitary device for protecting a generator of high frequency heating current, which has associated grid and anode circuits, from damage due to abnormal flow of current in either of said circuits, said device comprising a resistor, a part of which is so connected in one of said circuits and the remainder of which is so connected in the other of said circuits that on normal flow of current in each of said circuits the voltage drops across each of said parts of the resistor is substantially equal, means for adjusting the relative values of said parts of said resistors, and a relay for de-energizing said generator and having its actuating winding connected in parallel with said resistor.

ROBERT F. HOLTZ.
